UNITED STATES PATENT OFFICE.

ARTHUR F. HALL, OF TORONTO, ONTARIO, CANADA.

RAIL-JOINT.

1,008,259.

Specification of Letters Patent.

Patented Nov. 7, 1911.

Application filed June 10, 1911. Serial No. 632,318.

To all whom it may concern:

Be it known that I, ARTHUR F. HALL, a subject of the King of Great Britain, and a resident of Toronto, in the Province of Ontario and Dominion of Canada, have invented a new and Improved Rail-Joint, of which the following is a full, clear, and exact description.

My invention relates to rail joints, and it has for its object to provide one which distributes the strain and provides a secure and substantial joint, presenting a smooth and continuous surface to the wheels.

Another object of the invention is to provide a rail joint which will protect the ends of rails.

Still other objects of the invention will appear in the following complete specification, in which the preferred form of the invention is disclosed.

In the drawings similar characters of reference indicate corresponding parts in all the views, in which—

Figure 1 is a perspective view showing the end of one of the rails used with my joint; Fig. 2 is a side elevation of the neighboring ends of two rails, used with my joint; Fig. 3 is a view similar to that shown in Fig. 2 but showing one of the side plates in position; Fig. 4 is a view similar to that shown in Fig. 3, but with the saddle member in position; Fig. 5 is a sectional view on the line 5—5 of Fig. 4; Fig. 6 is a perspective view showing one of the side plates; and Fig. 7 is an end view of a rail showing how rails of standard construction may be altered so that they may be used with my improvement.

By referring to the drawings it will be seen that the rail 5 is provided with shoulders 6, spaced from and disposed below the plane at the bottom 7 of the head 8 of the said rail, there being one of the shoulders 6 at each side of the rail. The tops of the heads 8 are removed at the ends of the rails 10 forming recesses 9. In the web 11 of the rail 5, there are elongated holes 12 and 13, the elongated hole 12 being disposed below the recess 9, while the elongated hole 13 is disposed under the head 8 at the inner sides of the said recess 9.

The rails 5 are disposed in alinement, and side plates 14 are disposed one at each side of the rails, at their neighboring ends, the

side plates 14 having inwardly disposed shoulders 15 at their upper portions. The tops of the plates 14 engage the shoulders 6, of the rail, and the shoulders 15 of the plates 14 press against the upper portion of the web 11 of the rail. The base flanges 16 of the plates 14 rest on the flanges 17 of the rails 5. The base flanges 16 have their lower edges bent downwardly at 18, and in these lower edges 18 there are recesses 19, in which spikes may be driven.

As best shown in Fig. 6 of the drawings the side plates 14 have shoulders 20, at their ends. There are also holes 21 through the plates 14, which are adapted to register with the holes 12 and 13 in the webs 11 of the rails. Saddle members 22 are provided for connecting the heads 8 of the rails, the saddle members 22 having central portions 23 which are normally disposed in the recess 9, as best shown in Fig. 4 of the drawings. The saddle members 22 also have depending portions 24, which are disposed against the outer sides of the side plates 14, between the shoulders 20 of the said side plates. There are holes 25 through the depending portions 24, of the saddle members 22, the said holes 25 registering with the central holes 21 in the side plates 14, and also with the holes 12 in the webs 11 of the rails, so that bolts 26 may be inserted therein to hold the saddle members 22, and the side plates 14 in position.

As shown in Fig. 7 of the drawings a rail 27 of standard construction may have the portion above and at the outer sides of the line 28, cut away, which will permit it to be used with my side plates 24 and saddle member 22. However, I prefer to use the specially constructed rail shown in Fig. 1 of the drawings.

In using the invention, after the rails are disposed in position, as shown in Fig. 2 of the drawings, the side plates 14 are mounted one at each side of the rails, as has been stated, with the shoulders 15 pressing against the webs 11 of the rail, and with their upper portions engaging the shoulders 6 of the rail. The shoulders 6 provide a bearing surface for the upper portions of the plates 14, while the shoulders 15 of the said plates 14 prevent the upper portions of the side plates from being drawn inwardly, when the nuts 26 are turned home on the bolts.

26. The shoulders 20 of the side plates 14 prevent the members of the joint from creeping.

As will be readily understood the saddle 5 22, in connection with the heads of the rails, presents a smooth and continuous surface to the wheels, and as the wheels pass over the saddle the strain on the plates is distributed throughout the length of the saddle, 10 thus greatly reducing the possibility of fracture of the parts. As the necessary space between the ends of the rails is divided and there need be only one-half of the said space between the end of the saddle, and the end of 15 the head of a rail at the cut-away portion, there is no possibility of the rails becoming flattened or chipping at their ends, and the jar to the rolling stock as the wheels pass over the ends of the rails is greatly reduced. 20 It will be understood that should the saddle 22 become damaged or should it be found that it does not fit snugly enough in the recesses in the heads of the rails, it may be readily replaced by another saddle member, 25 which will meet the requirements.

Having thus described my invention, I claim as new and desire to secure by Letters Patent:

1. In combination with two rails disposed 30 normally in alinement and having heads with recesses at their neighboring ends, plates disposed one at each side of the rails at their said ends; a saddle member having a central portion disposed in the recesses 35 of the heads of the rails and depending portions disposed against the side plates, and means for securing the saddle member to the rails.

2. In combination with two rails with 40 heads and normally disposed in alinement, the rails having shoulders at their sides, the tops of the heads of the rails at the neighboring ends of the rails being removed to form recesses, plates disposed one at each 45 side of the rails at the said ends and disposed against the said shoulders, a saddle member having a central portion disposed in the recesses of the heads of the rails and depending portions disposed against the side 50 plates, and means for securing the saddle member to the rails.

3. In combination with two rails normally disposed in alinement and having heads with recesses at their neighboring ends, plates 55 having shoulders at their ends disposed one at each side of the rails at the neighboring ends of the rails, a saddle member having a central portion disposed in the recesses in the heads of the rails, and depending portions disposed against the sides of the plates 60 between the shoulders of the said plates, and means for securing the saddle to the rails.

4. In combination with two rails with 65 heads and normally disposed in alinement, the rails having shoulders at their sides, the

tops of the head of the rails at their neighboring ends being removed to form recesses, plates disposed one at each side of the rails, at the said ends of the rails and having shoulders at their ends, a saddle member 70 having a central portion disposed in the recesses in the heads of the rails, and depending portions disposed against the side plates between the shoulders of the side plates, and means for securing the saddle member to 75 the rails.

5. In combination with two rails normally disposed in alinement and having heads with recesses at their neighboring ends, plates disposed one at each side of the rails at the 80 said ends, and having inwardly disposed shoulders at their upper portions for engaging the rails, a saddle member having a central portion disposed in the recesses in the heads of the rails, and depending portions 85 disposed against the side plates, and means for securing the saddle member to the rails.

6. In combination with two rails with 90 heads and normally disposed in alinement, the rails having shoulders at their sides, the tops of the heads of the rails at their neighboring ends being removed to form recesses, plates having shoulders at their ends disposed one at each side of the rails at the said 95 ends of the rails, and having inwardly disposed shoulders at their upper portions for engaging the rails, a saddle member having a central portion disposed in the recesses in the heads of the rails, and depending portions disposed against the side plates between the shoulders of the side plates, and means for securing the saddle member to the rails.

7. In combination with two rails with 100 heads, and normally disposed in alinement, the rails having shoulders at their sides, the tops of the heads of the rails at their neighboring ends being removed to form recesses, plates disposed one at each side of the rails at the said ends of the rails, and having inwardly disposed shoulders at their upper portions, for engaging the rails, and a saddle member having a central portion disposed in the recesses in the heads of the rails, and depending portions disposed against the side 110 plates, and means for securing the saddle member to the rails.

8. In combination with two rails disposed 115 normally in alinement and having transverse openings and heads with recesses at their neighboring ends, plates having transverse openings disposed one at each side of the rails at their said ends, a saddle member having a central portion disposed in the recesses in the heads of the rails and depending portions with transverse openings disposed against the side plates, and bolts disposed in the openings for holding the rails, the plates and the saddle members in position.

9. In combination with two rails with heads and normally disposed in alinement, the tops of the heads of the rails at their neighboring ends being removed to form recesses, plates having shoulders at their ends and having inwardly disposed shoulders at their upper portion for engaging the rails, a saddle member having a central portion disposed in the recesses in the heads of the rails, and depending portions disposed against the side plates between the shoulders of the side plates, and means securing the saddle member to the rails.
10. In combination with two rails with flanges and heads disposed normally in alinement, the rails having shoulders spaced from the longitudinal, horizontal plane of the heads and from the flanges of the rails, the tops of the heads of the rails at their neighboring ends being removed to form recesses, a saddle member having a central portion disposed in the recesses in the ends of the rails, and depending portions dis-
- posed one at each side of the rails and against the shoulders, and means for securing the saddle member to the rails.
11. In combination with two rails having heads disposed normally in alinement the rails having shoulders spaced from the longitudinal plane of the heads, the tops of the heads of the rails at their neighboring ends being removed to form recesses, plates disposed one at each side of the rails at the said ends, and engaging the shoulders of the rails, a saddle member having central portions disposed in the recesses in the ends of the rails and a depending portion disposed against the side plates, and means for securing the saddle member to the rails.
- In testimony whereof I have signed my name to this specification in the presence of two subscribing witnesses.
